O. A. STEMPEL.

BOX-FASTENER.

No. 173,365.

Patented Feb. 8, 1876.

FIG. 1.

FIG. 2.

UNITED STATES PATENT OFFICE.

OMAR A. STEMPLE, OF MORRISON, MISSOURI.

IMPROVEMENT IN BOX-FASTENERS.

Specification forming part of Letters Patent No. 173,365, dated February 8, 1876; application filed December 1, 1875.

To all whom it may concern:

Be it known that I, OMAR A. STEMPLE, of Morrison, in the county of Gasconade and State of Missouri, have invented a new and useful Improvement in Egg-Boxes, which improvement is fully set forth in the following specification, reference being had to the accompanying drawings.

My improvement consists in the provision, in a recess at front of the sliding lid, of a metallic plate, through which passes a pin engaging in the front end of the case, and which is secured in position while the box is in transit by a sliding plate, which is itself held in position by a seal occupying the space in the recess, into which the lock-plate slides to disclose the top of the lock-pin.

Figure 1 is a perspective view of the upper portion of a box with part of the cover removed. Fig. 2 is an enlarged longitudinal section.

The box is made of the ordinary size to contain two piles of the ordinary cell-trays, in which eggs are shipped.

The box consists of a bottom, (not shown,) sides A A', ends B B', division-piece C, extending across the box at its mid-length, and lid D, sliding endwise into place. E E are hand-cleats, by which the box may be lifted. F F are metallic cleats, provided with lips f, and secured to the upper edge of piece C, and let into and secured to the sides A A' by rivets a, so that the box is prevented from spreading open at the middle.

These metallic cleats I intend to make the subject-matter of another application for Letters Patent.

At the front end of the lid is a metallic lock-piece, G, firmly secured to the lid, and through this and through the part d of the lid (extending downward at the front end) is a pin-

hole, H, which extends down into the end B, and whose lower end curves inward and extends to the inside of the end, so as to give means of exit to any matter that may enter the hole H. I is the locking-pin, which is dropped into the hole H from the top. The pin may consist of a common cut-nail.

The lock-piece G has a recess, G¹, in which slides a plate, K, the plate being held down by ribs g upon the inner sides of the recess G¹. The arrangement is such that the plate may be slid inward to uncover the top of pin I, to allow the withdrawal of the pin, or slid outward to cover the top of the pin and prevent its withdrawal. The bottom of the recess G¹ is roughened at G², so as to hold the seal G³, which is made to fill that part of the recess behind the plate K when it is in its forward position, to prevent the movement of the plate without destruction of the seal.

The plate K has a recess, K', upon the lower side, which decreases in depth backward, and the piece G has a stud, g², which, as the plate K is moved forward over the pin I, presses against the under side of the plate in the groove, and springs the plate outward, so as to bind it in its side guides, and so hold it in place before the application of the seal.

At the inner end of the plate K is a wedge-formed projection, K², for the easy demolishing of the seal when the plate is driven back, (to allow the removal of the locking-pin.)

I claim as my invention—

The locking device composed of end B, sliding lid D, pin-hole H, pin I, sliding plate K, and seal G³, substantially as set forth.

OMAR A. STEMPLE.
